UNITED STATES PATENT OFFICE.

FRANK J. HORSTMAN, OF HAVANA, ILLINOIS, ASSIGNEE TO HORSTMAN MANUFACTURING COMPANY, OF CHICAGO, ILLINOIS.

HOROLOGICAL INSTRUMENT.

1,085,206.

Specification of Letters Patent.

Patented Jan. 27, 1914.

Application filed April 25, 1911. Serial No. 323,200.

To all whom it may concern:

Be it known that I, FRANK J. HORSTMAN, a citizen of the United States, residing at Havana, in the county of Mason and State of Illinois, have invented a certain new and useful Improvement in Horological Instruments, of which the following is a full, clear, concise, and exact description, reference being had to the accompanying drawings, forming a part of this specification.

My invention relates to horological instruments and more particularly to such instruments in which the movement or driving mechanism thereof is mounted on and carried by the hands thereof. When a device of this kind is utilized for time indicating purposes two hands are used which are the ordinary hour hand and minute hand and each hand is provided with a timing mechanism or movement commonly called a horological motor which is pivotally mounted and unequally balanced so that the rotation of the said movement will disturb the equilibrium of the hand and cause the hand to rotate in response to operations of the movement. My invention is particularly concerned with improvements in instruments of this character so as to make them of greater applicability, and to provide them with means of proper adjustment so that they may be accommodated, or accommodate themselves to different temperatures or other changed conditions of operation. My structure also enables me to make a device very light and easily balanced so that it will operate more accurately. Improved means for mounting the driving mechanism are also features of my invention.

My invention in its preferred form also contemplates improved means for mounting the device to a suitable support and also improved means for setting the motor mechanism accurately before the device is started in motion.

I will describe my invention more in detail by reference to the accompanying drawing illustrating the preferred embodiment thereof, in which:

Figure 1 is a front view of a clock embodying my invention; Fig. 2 is a detail view of the setting mechanism; Fig. 3 is a detail view of the means for associating the movement to the hour hand; Figs. 4 and

attachment of the inclosing cap; Fig. 6 is a side view of the device as illustrated in Fig. 1; Fig. 7 is a detail view of the mounting means; Fig. 8 is a detail view of the adjusting device; Fig. 9 is a cross-sectional view of the device set forth in Fig. 8; Fig. 10 is a detail view of the spring cap associated with the mechanism of Fig. 7, and Fig. 11 is a detail view showing the attachment of the movement to the minute hand.

Referring more particularly to Fig. 1, I set forth a dial 1 provided with indicia 2. Two hands, respectively a minute hand 3 and an hour hand 4 pivoted at 5 coöperate with the dial 1 to indicate the time. Each hand is provided with a watch or clock movement, the hour hand 4 having the movement 6 and the minute hand 3 having the movement 7. Caps of wood 8 inclose the movements and are fastened to the hands 9. The hands are provided with bolts 10 and sockets 11, are provided in the caps 8, which sockets are of a bayonet character, as illustrated in Figs. 4 and 5, so that the caps may be inserted in place around the bolts 10, whereafter a slight rotation of the said caps 8 serves to bring projecting portions thereof under the heads of the bolts 10, whereby to hold these caps in place and to make them readily removable and replaceable.

In the illustration of Fig. 3 I show the hour wheel 12 whose projecting sleeve is frictionally engaged with a slot provided in a bolt 13 so as to hold the said hour wheel 12 securely against the said bolt so that the movement 6 may rotate once every twelve hours about the bolt 13 as an axis. A nut 14 holds the bolt 13 in place on the hand 4.

Referring to Fig. 11 the improved means for mounting the clock mechanism to the minute hand are set forth and these means comprise a center arbor 15 forming part of the center wheel 16, or being otherwise rigidly secured thereto, which center arbor 15 is fixedly secured within the bolt 17 provided in the hand 3. The bolt 17 is held in place by a nut 18. In this manner it will be seen that the movement 7 rotates once an hour around the bolt 17 as an axis. As the great bulk of the weight of these movements is eccentric as respects their axis of rotation, the rotating of these movements disturbs the equilibrium of the pivotally mounted hands to which they are associated,

and thereby causes rotation of these hands about their pivotal mounting 5, thereby to indicate the time in accordance with the actuations of the movements 6 and 7.

In Figs. 7 and 10, I have illustrated improved means for supporting the hands 3 and 4. In these views as also in Fig. 6, I show a pane of glass 19 to which a transparent dial 20 may be attached. A conical wooden support 21 is provided which is glued to the glass 19 at 22 and this wooden support 21 holds the hands 3 and 4. The hands 3 and 4 are mounted upon a spindle 23 which projects from the support 21. The hand 3 has a hole drilled in the proper place for mounting purposes, which hole is bushed by means of a hollow metallic sleeve 24 held in place on said hand by means of a nut 25. The hour hand 4 is also properly drilled and is provided with a metallic sleeve 26 held in place by the nut 27. These sleeves are mounted upon the spindle 23 and a cylindrical distance piece 28 is provided between them to aline them and prevent interference between them. In order to hold the hands and the distance piece 28 properly upon the spindle, I use a split friction sleeve 29 illustrated in Figs. 6, 7 and 10 which is placed into frictional engagement with the said spindle 23 and is securely held in place frictionally thereon.

In order properly to balance the hands so that they will move accurately in response to the rotations of movements associated therewith, it is essential that very delicate and easily adjustable means are provided, and these are set forth more in detail in Figs. 8 and 9. These means concerned are provided upon both hands and consist of two guides 30, 30 between which a metallic serrated rod 31 is placed which is movable longitudinally of the hand with which it is associated. A spring catch 32 having two projecting arms 33, 33 engages the serrations of the element 31 and holds the same in the position in which it has been placed. The arms 33 extend into the guide 30 and hold the said spring catch in place.

An important feature of my invention 50 contemplates means for setting the movement to the desired hour of day before the hands are mounted in place upon their rotatable support, and this means is more clearly illustrated in Fig. 2. In this figure the hand

4 has a supplemental dial composed of the 55 hour numerals, or minute numerals in the case of the minute hand; in coöperation with which numerals I provide a lug 34 associated with the movement 6. As the movement rotates about its center pivotal point 60 the lug 34 points to the exact hour to which the hand would point with the hand pivotally mounted on its support. In this manner the mechanism may be properly set to the desired hour before the hands are placed 65 in their operative position upon the spindle 23.

The various novel features of my invention will thus be clear and while I have described these features specifically with relation to one form which these specific features may take, I do not limit myself to such specific construction and arrangement as the invention is capable of a variety of modifications and uses, but

Having thus described one form of carrying out my invention, what I claim as new and desire to secure by Letters Patent is:

1. A device of the character described having a pivotally mounted hand, a horological motor for driving same carried by said hand, said motor having a center arbor, and means for frictionally securing said center arbor to the hand, said means including a metallic bushing of hollow interior for 80 engaging said arbor, and a nut for securing said bushing to the hand.

2. A device of the character described having a pivotally mounted hand, a horological motor near one extremity of said hand, and means mounted upon said hand for adjusting the center of gravity thereof, said means including a serrated weight element, and spring retaining means therefor.

3. A device of the character described having a pivotally mounted hand, a horological motor near one extremity of said hand, and means mounted upon said hand for adjusting the center of gravity thereof, said means including a serrated weight element, guides for said element, and spring retaining means therefor.

In witness whereof, I hereunto subscribe my name this 20th day of April, A. D., 1911.

FRANK J. HORSTMAN.
